FURNACE STOKER

Leonard A. Ward, Denver, Colo.

Application December 14, 1936, Serial No. 115,714

5 Claims. (Cl. 110—101)

This invention relates to a stoker for feeding coal to a furnace and while more particularly adapted for feeding fuel to household furnaces and heating plants it will be found useful 5 wherever a positive controlled fuel and air feeding device is required.

The principal object of the invention is to provide a stoker of this character which will occupy but a minimum of space; which will be quiet in 10 operation; which will positively and uniformly feed the fuel to the fire; which will automatically break and size the fuel to the proper feeding size; and which can be easily and accurately adjusted both as to air supply and coal supply.

15 Other objects and advantages reside in the detail construction of the invention, which is designed for simplicity, economy, and efficiency. These will become more apparent from the following description.

20 In the following detailed description of the invention reference is had to the accompanying drawings which form a part hereof. Like numerals refer to like parts in all views of the drawings and throughout the description.

25 In the drawings:

Fig. 1 is a plan view of the improved stoker with the hopper bottom thereof partially broken away to show the feeding mechanism.

Fig. 2 is a section through the stoker housing, 30 taken on the line 2—2, Fig. 1, illustrating a side elevation of the operating mechanism.

Fig. 3 is a vertical section, taken on the line 3—3, Fig. 2.

Fig. 4 is a detail section through the upper extremity of the fuel feed tube.

Fig. 5 is a detail view illustrating the breaker plate employed in the invention.

Fig. 6 is a vertical section, taken on the line 6—6, Fig. 3.

40 Fig. 7 is a detail section, illustrating the burner extremity of the stoker.

The entire coal supply and operating mechanism is enclosed within an ornamental rectangular enclosing housing 10, supported upon suitable 45 legs 11. In the upper part of the housing 10 a coal hopper 12 is formed into which coal may be fed through the open top of the housing 10.

The bottom of the coal hopper 12 opens to a 50 feed screw chamber 13 in which a feed screw 14 is positioned. The coal is prevented from arching over the feed screw chamber 13 by means of an agitator 15. At the discharge extremity of the feed screw chamber 13 is a feed chute 16, the spout of which feeds the coal into the upper extremity of a feed tube 17. The feed tube 17 is

inclined downwardly toward its discharge extremity and terminates over an air distributor 18 within the fire box of the furnace.

Air is fed to the air distributor 18 through a suitable conduit 19 from a blower 20. The blower 5 is driven from an electric motor 21 which also operates the entire feed mechanism. The shaft of the motor 21 extends through the blower 20 as shown at 55 and terminates on the opposite side thereof in a worm 22, which is enclosed 10 within a worm gear housing 23. The worm 22 acts to rotate the feed tube 17 through the medium of a worm gear 24 which is fixed to and rotates with the feed tube. The latter is carried in a bearing sleeve 25 which serves to support it 15 and maintain it at the proper angle.

The feed screw 14 forces the coal along the chamber 13 and through a serrated breaker plate 26 provided with breaking teeth 27. All large chunks of coal are broken up and reduced to 20 small pieces as they enter the chute 16. The shaft of the feed screw extends through the chute 16 and is provided with a finger 28 which breaks loose any particles of coal caught in the breaker plate 26 and prevents packing in the chute. The 25 upper extremity of the feed tube 17 is also provided with an agitating finger 29 which extends within the chute 16 to loosen any coal which may clog in the discharge thereof.

The feed screw 14 is intermittently rotated by 30 means of a friction wheel 30. The wheel 30 is mounted on one extremity of the feed screw shaft and is rotated from a reciprocating pawl lever 31 carrying a friction pawl 32. The lever 31 is also mounted on the feed shaft which serves as a 35 pivot therefor. The panel 32 is pivoted to the lever by means of a suitable hinge pin 36. A return pawl 33 prevents return rotation of the ratchet wheel 30.

The pawl lever 31 is reciprocated through the 40 medium of a connecting rod 34 from a bell crank lever 35, the other arm of which terminates in a roller 36 which rides against a cam 37 on the feed tube 17. A coil spring 38 constantly pulls the roller 36 against the cam 37. The eccentric 45 contour of the cam 37 imparts a rocking movement to the bell crank lever 35, which in turn imparts a similar movement to the cam lever 31, causing the screw 14 to be advanced a short interval at every revolution of the feed tube 17. 50

The amount of movement of the feed screw is of course dependent upon the arc of movement of the lever 31, and this arc of movement can be regulated by means of a regulating knob 39 which places a cam 40 in the path of movement 55

of the lever 31. Thus, if the cam 40 is turned upwardly, the lever 31 will contact with it on its return stroke. This will hold the roller 36 out of contact with the cam 37 so that the rocker arm 35 will not receive a full reciprocation. In this way, the amount of coal fed can be accurately regulated.

The agitator 15 terminates on the exterior of the hopper 12 in a slotted arm 41, the slot of which rides over a crank pin 42 on the ratchet wheel 30. Thus, rotation of the ratchet wheel will move the agitator 15 to keep the coal flowing from the hopper to the feed screw 14.

The amount of air can be regulated by means 15 of an air regulating knob 42 which is operatively connected to a damper 43 on the intake of the blower 20. An auxiliary air pipe 44 may be placed from the conduit 19 extending into the chute 16 to blow any fumes which may ascend 20 in the feed tube downwardly and outwardly into the furnace. It is preferred, however, to place a suction pipe 55 from the suction side of the blower to the chute 16 to draw out any fumes which may collect in the feed tube and chute.

25 The delivery extremity of the feed tube is preferably formed with a helical agitator 45 which acts to distribute the incoming coal over the surface of the air distributor 18.

30 While a specific form of the improvement has been described and illustrated herein, it is desired to be understood that the same may be varied, within the scope of the appended claims, without departing from the spirit of the invention.

35 Having thus described the invention, what is claimed and desired secured by Letters Patent is:

1. Means for feeding solid fuel to a burner comprising: a feed hopper; a feed screw in the bottom of said hopper; a receiving chute for receiving the fuel from said screw; an inclined feed tube extending from said chute to said burner; means for rotating said feed tube; a cam surface carried by said feed tube; and a lever contacting said cam to impart an intermittent rotation to said feed screw as said tube rotates.

40 2. Means for feeding solid fuel to a burner comprising: a feed hopper; a feed screw in the bottom of said hopper; a receiving chute for receiving the fuel from said screw; an inclined feed tube

extending from said chute to said burner; means for rotating said feed tube; a wheel on said feed screw; a pawl lever positioned adjacent said wheel; a pawl on said lever for rotating said wheel; a cam on said feed tube; and means riding on said cam for reciprocating said pawl lever.

45 3. Means for feeding solid fuel to a burner comprising: a feed hopper; a feed screw in the bottom of said hopper; a receiving chute for receiving the fuel from said screw; an inclined feed tube extending from said chute to said burner; means for rotating said feed tube; a wheel on said feed screw; a pawl lever positioned adjacent said wheel; a pawl on said lever for rotating said wheel; a cam on said feed tube; means riding on said cam for reciprocating said pawl lever; and manually adjustable means for limiting the return movement of said pawl lever.

20 4. A stoker comprising: an enclosing, open-topped housing; a hopper bottom in the upper portion said housing; a feed screw chamber in said hopper bottom; a burner, a receiving chute at the extremity of said screw chamber; an inclined, rotatably mounted feed tube extending from said receiving chute to said burner; a blower 25 positioned adjacent said feed tube; a conduit extending from said blower into said burner and terminating at the discharge extremity of said feed tube; an air distributor on the inner extremity of said conduit for receiving the fuel discharged from said tube; means for rotating said feed tube; a cam surrounding said feed tube; a lever riding against said cam; and means for transmitting the movement of said lever to said feed screw.

25 5. In a stoker of the type having a rotary inclined feed tube, means for feeding fuel into said feed tube comprising: a screw type conveyor positioned to deliver fuel to said feed tube; an annular eccentric cam surrounding said feed tube; a cam follower bearing against said cam; a wheel on said feed screw; and a pawl actuated by said cam follower in contact with said wheel so that rotation of said feed tube will cause said pawl to reciprocate said follower to cause the latter to intermittently actuate said wheel and through it said feed screw.

LEONARD A. WARD.
